Sidney A. Sweet, Tyngham, Massachusetts.
Pitter's Patent.

Dated December 31st 1833.

The Schedule referred to in this Pitter's Patent and making part of the same, containing a description in the words of the said Sidney A. Sweet himself, of his improvement called the Horizontal Pulp Sifter.

Be it known, that I, Sidney A. Sweet, of Tyngham, in the County of Berk-
shire, and State of Massachusetts, have made a new and useful improvement in
the useful art, called the Horizontal Pulp Sifter, which is described as follows;
referring back to the annexed drawing.

This pulp sifter consists of a metallic plate, a having incisions or fine
slits made thro' the same to permit the passage of the pulp, which slits should be
sufficiently narrow to detain the knots, and other impurities, usually floating
or formed therein. The plate is surrounded by a border or frame of wood, b, so
high as to prevent the overflow of the pulp. This pulp sifter should be placed hori-
zontally in a situation convenient for receiving the pulp after its mixture
with water, the pulp having passed through the sifter should be carried to
the part where it is to be used. The operation or manner of forcing the pulp through
the pulp sifter is by a jarring motion produced by shaking the same, or one or both
ends of it, a small distance and then suffering it again to fall suddenly
upon some solid fixture. This motion should be rapidly repeated, and may be
produced by many and various ways already known.

What I claim as my invention is, the before described manner of con-
structing the Horizontal Pulp Sifter, and the mode of operating it for sifting
or dressing pulp for the manufacture of paper.

Witnessed,

William P. Elliot
